FABRIC.

No. 17,489.

Patented July 26, 1887

UNITED STATES PATENT OFFICE.

MARTIN LANDENBERGER, JR., OF PHILADELPHIA, PENNSYLVANIA, AS-
SIGNOR TO THE E. H. GODSHALK COMPANY, OF SAME PLACE.

DESIGN FOR FABRIC.

SPECIFICATION forming part of Design No. 17,489, dated July 26, 1887.

Application filed May 14, 1887. Serial No. 238,274. Term of patent 3½ years.

To all whom it may concern:

Be it known that I, MARTIN LANDENBERGER, Jr., a citizen of the United States, residing in the city and county of Philadelphia, State of Pennsylvania, have invented and produced a new and original Design for Fabrics, of which the following is a specification, reference being had to the accompanying photograph, forming part thereof.

The leading features of my design for fabrics are stripes of wave or zigzag form having fluffy faces alternating with stripes of wave or zigzag form having plain or comparatively plain faces.

A represents a piece of fabric having stripes *a b.*

The stripes *a* are fluffy, of comparatively uniform elevation, and of wave or zigzag form. The stripes *b* are comparatively plain, and alternate with the stripes *a*.
